UNITED STATES PATENT OFFICE

92,121

DESIGN FOR AN OPEN-END MULTIPLE CHEESE SLICER

Katharine B. Wagner, Sidney, Ohio

Application January 19, 1934, Serial No. 50,454

Term of patent 14 years

To all whom it may concern:

Be it known that I, KATHARINE B. WAGNER, a citizen of the United States, residing in the city of Sidney, in the county of Shelby and State of Ohio, have invented a new, original, and ornamental Design for an Open-End Multiple Cheese Slicer, of which the following is a specification, reference being had to the accompanying drawing, forming part hereof.

The figure is a perspective view of an open-end multiple cheese slicer, showing my new design, the dotted lines representing a block of cheese.

I claim:

The ornamental design for an open-end multiple cheese slicer, as shown and described.

KATHARINE B. WAGNER.
